LINE INDICATOR

Vincent J. Gilmore, Wappingers Falls, N.Y., assignor to International Business Machines Corporation, New York, N.Y., a corporation of New York

Application July 9, 1956, Serial No. 596,541

6 Claims. (Cl. 197—189)

This invention relates to typewriters, and more particularly to a device for visibly indicating the extent of movement of a sheet of paper through a typewriter.

The primary object of the invention is to provide an improved device operatively connected to a platen shaft of a typewriter to indicate visibly the position of the lower edge of the paper sheet relative to the line being typed.

Another object of the invention is to provide for a typewriter, an improved line indicating device which can be positioned independently of the movement of the typewriter platen.

A further object of the invention is to provide a line indicating device which can be reset rapidly and easily by the operator.

In the preferred form of the invention, the line indicating device is connected to the platen shaft by a clutch which permits the operator to disconnect the indicator from the platen to position the paper sheet and to set the indicator on any desired position. With the clutch engaged, a gear moves with the platen shaft and drives a gear train which positions an indicator scale according to the vertical movement of the paper sheet. When typing is completed near the end of the sheet, the clutch is disengaged allowing a spring to return the indicator scale to its home position.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is an enlarged side elevational view, partly in vertical section, of the indicating device.

Fig. 2 is a vertical section taken on line 2—2 of Fig. 1.

Referring to Fig. 1, it will be noted that there is shown a platen shaft 1 journaled in a bearing member 2 supported by a carriage frame 3 of a typewriter. Formed integrally with the bearing member are flange portions 4 engaging opposite surfaces on the carriage frame for holding the member against axial movement. The platen shaft 1 passes through a sleeve 6 and an insert member 8 of cylindrical shape. The sleeve 6 extends into an enlarged bore at one end of the insert member 8 and is coupled to the latter and to the shaft by a screw 9 in such a manner that they rotate as a unit. The sleeve 6 and member 8 have a sliding fit on the shaft 1, and, in order that they may be moved axially a limited amount relative to the shaft, there are provided elongated slots 10 and 11 in the sleeve and member 8, respectively, through which the screw 9 passes. Mounted upon the member 8 with a force fit is a knob 12 which may be operated manually for either rotating the platen shaft or for moving the member 8 and the sleeve 6 axially.

As shown in Fig. 1, the platen knob 12 is in the extreme right-hand position; hereafter called the operating position. By moving the platen knob 12 to the left, the

2

insert member 8 and the sleeve 6 are positioned in the extreme left-hand position hereafter called the detent position, where a detent ball 14 is urged by a spring 16 into an opening 18 in the insert member 8 to retain the parts in such a position without manual effort.

The sleeve 6 passes through a drive pinion 20 which has a friction washer 22 attached to its face opposite an enlarged portion 23 of sleeve. A coil spring 24 is positioned around the shaft 1 within the sleeve portion 23 and acts between a flange 25 on the shaft and the sleeve 6 to force the latter against the friction washer 22. In the operative position, the friction washer 22 and the portion 23 of the sleeve 6 are engaged so that the drive pinion 20 is caused to rotate with the shaft 1. When the platen knob 12 is in the detented position, the sleeve 6 is displaced to the left along the shaft 1, and the driving engagement between the sleeve 6 and the drive pinion 20 is broken so that the latter turns freely about the sleeve.

As shown in Fig. 2, the drive pinion 20 is constantly meshed with an idler gear 28 which is rotatably supported on a cylindrical member 30 by a screw 32. The member 30 is disposed about the sleeve 6 and the insert member 8 and is arranged for manual rotation with respect to the shaft. Formed in an inner surface of the member 30 is an annular recess 31 which receives the head of the screw 9 to prevent movement of the member longitudinally of the shaft 1 while permitting it to rotate relative thereto. Formed in the member 30 is an opening 33 through which the screw 9 may be inserted or removed. For preventing rotation of the member 30 other than by manual setting, there is provided a detent pin 34 which is held by a spring 35 in engagement with serrations 36 on the outer periphery of the member 30.

The idler gear 28 is constantly in mesh with the teeth of an internal or ring gear 40 which is supported for rotation on the enlarged portion 23 of sleeve 6 and carries a numerical scale on its outer surface. Surrounding the sleeve 6 is a torsion spring 42 which is connected at one end to a stud 44 on the indicator gear 40 and is connected at its other end to a projection 46 on the member 30. Formed on the indicator gear 40 is a lug 48 which is engageable with the projection 46, and the spring 42 tends to turn the gear 40 counter-clockwise in Fig. 2 until the lug 48 engages the projection 46 as shown. As the platen is rotated in a paper feeding direction, the indicator gear is driven clockwise in Fig. 2 by the gears 20, 28. The member 30 carrying the projection 46 is held against rotation during this time by the detent pin 34. Rotation of the indicator gear relative to the member 30 is limited to 354° since the lug 48 then engages the opposite side of the projection 46.

At the beginning of a typing operation, the platen knob 12 is moved to the left to disengage the sleeve 6 from the drive pinion 20. If the lug 48 on the indicator gear 40 is not engaging the projection 46 on the member 30 at that time, then the spring 42 operates to rotate the gear 40 counter-clockwise in Fig. 2 until such engagement takes place. When the knob 12 is moved to the left, the detent 14 engages the opening 18 to hold the sleeve 6 disengaged from the gear 20 while the knob is rotated to feed a paper sheet to its first typing line.

With the paper in typing position, the member 30 is rotated manually to effect a turning of the gear 40 for positioning the indicator scale relative to an index line 50 marked on the upper surface of the carriage frame adjacent a view window 51. If the member 30 is turned in one direction, its projecting portion 46 acts against the lug 48 and forces the gear 40 to turn in the same direction. Rotation of the member 30 in the opposite direction tends to move the projection 46 away from

the lug 48 but the spring 42 holds the lug against the projection so that the gear 40 follows the member 30.

The scale on the periphery of the gear 40 may indicate either the travel of the platen surface in inches or the number of lines typed or to be typed. If desired, there may be provided different scales depending upon the information desired. Scales indicating the number of lines typed or the travel of the platen surface in inches from the first line typed would increase progressively in a counter-clockwise direction in Fig. 2. In this case, the member 30 would be rotated, after the paper was advanced to position for typing a first line, until the zero point on the scale came under the index line 50. Scales indicating the space remaining on a sheet in terms of lines or inches would increase in a clockwise direction around the indicator gear 40. When these scales are used, the member 30 is rotated until the value indicating the maximum number of lines or inches within a space to be typed is under the index line 50.

After the member 30 has been positioned, the knob 12 is pulled outwardly on the platen shaft until the portion 23 of the sleeve 6 engages the friction washer 22 and operatively connects the gear 20 to the platen shaft. As the platen is rotated in a paper feeding direction, the gear 20 drives gear 28 to effect rotation of the indicator gear 40 for positioning the scale under the index line so as to provide an indication depending on the values used on the scale. When typing has been finished on a sheet of paper, the knob 12 is moved to the left for disengaging the sleeve portion 23 from the gear 20 and permitting the spring 42 to return the indicator gear to its home position. With the knob 12 in the detent position, a new sheet may be inserted without disturbing the initial setting. The first typing line is brought to position using the knob to turn the platen. Thereafter, the knob is returned to the operative position connecting the gear train to the shaft, and operation may proceed according to the previous description.

While there have been shown and described and pointed out the fundamental novel features of the invention as applied to a preferred embodiment, it will be understood that various omissions and substitutions and changes in the form and details of the device illustrated and in its operation may be made without departing from the spirit of the invention. It is the intention, therefore, to be limited only as indicated by the scope of the following claims.

What is claimed is:

1. A device for indicating the position of a paper sheet relative to the line of typing on the platen of a typewriter comprising, in combination, a shaft supporting said platen and having a portion extending from one end thereof, a sleeve shaped member slidably mounted on the extending portion of said shaft, means connecting said sleeve shaped member for rotation with said shaft but permitting limited movement axially of the latter, a driving gear freely mounted on said sleeve shaped member, clutch means for connecting said driving gear in driven relation with said sleeve shaped member, said clutch means being engaged by axial movement of said sleeve in one direction and disengaged by movement in the opposite direction, a spring urging said sleeve in a direction to engage said clutch means, a ring gear rotatably supported on said shaft portion, a cylindrical member rotatably supported on said shaft portion, detent means normally holding said cylindrical member against rotation, a gear rotatably supported by said cylindrical member and meshing with said driving gear and said ring gear, a projection on said cylindrical member, a lug on said ring gear engageable with said projection, a spring connected at its ends to said ring gear and said cylindrical member and tending to rotate them in opposite directions, a stationary frame portion adjacent to said ring gear and having an index line thereon, an indicator scale on said ring gear cooperating with said index line to provide a visual indica-

tion of the angular position of said gear, and means including a knob for moving said sleeve axially to disengage said clutch means and for rotating said platen shaft.

2. The device of claim 1 including detent means operable on moving said sleeve to its clutch disengaging position, for holding said sleeve in such position.

3. A device for indicating the position of a paper sheet relative to the line of typing on the platen of a typewriter comprising, in combination, a shaft supporting said platen and having a portion extending from one end thereof, a sleeve mounted on the extending portion of said shaft, means connecting said sleeve for rotation with said shaft but permitting movement axially of the latter, a driving gear, clutch means for connecting said driving gear in driven relation with said sleeve, said clutch means being engaged by axial movement of said sleeve in one direction and disengaged by movement in the opposite direction, means normally moving said sleeve in a direction to engage said clutch means, a ring gear arranged concentrically with said driving gear, a cylindrical member mounted on said shaft portion and adapted to be rotated manually, detent means for holding said cylindrical member normally against rotation, a gear rotatably supported by said cylindrical member and meshing with said driving gear and said ring gear, means tending to rotate said ring gear to a predetermined angular position relative to said cylindrical member, a stationary frame portion having an index line thereon, an indicator scale on said ring gear cooperating with said index line to provide a visual indication of the angular position of said gear, and manually operable means for moving said sleeve axially and for rotating said platen shaft.

4. In a typewriter having a carriage including a frame, a shaft rotatably supported in said frame, a platen fixed to said shaft and a feed mechanism for advancing the platen line by line, a device for indicating the relative rotation of said platen from a reference position on said frame comprising, in combination, a knob; a sleeve coaxial with said shaft and slidably and rotatably supported on the latter; means mounting said knob at an end of said sleeve, said means supported for axial movement on said shaft and adapted to slide said sleeve; means connecting said sleeve, said mounting means and said shaft for rotational movement; a driving gear rotatably supported on said sleeve; a friction member attached to said driving gear adapted to be selectively engaged by said sleeve; resilient means urging said sleeve into engagement with said friction member; a ring gear with indicia thereon rotatably supported around said sleeve; a cylindrical member rotatably supported on said mounting means; engaging means on said ring gear and said cylindrical member for establishing a home position; an idler gear rotatably attached to said cylindrical member and constantly in mesh with said driving gear and said ring gear; spring means urging said ring gear to a home position engaged with said cylindrical member; and detent means associated with said cylindrical member and said frame for maintaining a settable relation between said ring gear and said frame.

5. In a typewriter having a carriage including a carriage frame, a shaft rotatably supported in said frame, a platen fixed to said shaft, and a feed mechanism for advancing the platen line by line, a device for indicating the relative rotation of said platen from a reference position on said frame comprising, in combination, a knob; a sleeve coaxial with said shaft and slidably and rotatably supported on the latter; means coupling said knob to an end of said sleeve; means connecting said sleeve, said coupling means, and said shaft for rotational movement; a driving gear rotatably supported on said sleeve; clutch means for connecting said driving gear in driven relation with said sleeve, said clutch means being engaged by axial movement of said sleeve in one direction and disengaged by movement in the opposite direction; resilient

means urging said sleeve in a direction to engage said clutch means; a ring gear with indicia thereon rotatably supported about said sleeve; a cylindrical member rotatably supported on said coupling means; an idler gear rotatably attached to said cylindrical member and constantly in mesh with said driving gear and said ring gear; and detent means associated with said cylindrical member and said frame for maintaining a settable relation between said ring gear and said frame.

6. In a typewriter having a carriage including a carriage frame, a shaft rotatably supported on said frame, a platen fixed to said shaft, and a feed mechanism for advancing the platen line by line, a device for indicating the relative rotation of said platen from a reference position of said frame comprising, in combination, manually operable control means coupled to said shaft for rotation of the latter, said control means adapted to be moved axially with respect to said shaft, a driving gear rotatably

supported by said control means for movement about said shaft, clutch means normally coupling said driving gear and said control means and adapted to remove the coupling by axial movement of the control means, a ring gear with indicia thereon, said ring gear being rotatably supported by said control means, an adjusting member adapted for rotation with respect to said shaft for preliminary adjustment of said device, and an idler gear rotatably attached to said adjusting member and in mesh with said driving gear and said ring gear.
